ROBERT ROSS AND B. E. LEHMAN, OF BETHLEHEM, PENNSYLVANIA.

Letters Patent No. 65,609, dated June 11, 1867.

IMPROVEMENT IN LUBRICATORS.

The Schedule referred to in these Letters Patent and making part of the same.

TO ALL WHOM IT MAY CONCERN:

Be it known that we, R. Ross and B. E. LEHMAN, of Bethlehem, Northampton county, Pennsylvania, have invented an improvement in Oil-Cups; and we do hereby declare the following to be a full, clear, and exact description of the same, reference being had to the accompanying drawing, and to the letters of reference marked thereon.

Our invention consists of an oil-cup constructed in the peculiar manner fully described hereafter, so that it may be easily manipulated, and so that the oil may be freely discharged from it in a pure state.

In order to enable others skilled in the art to make and use our invention, we will now proceed to describe its construction and operation. On reference to the accompanying drawing, which forms a part of this specification—

Figures 1 and 2 are vertical sections of our improved oil-cup.

Figure 3, a sectional plan on the line 1-2, fig. 1.

Figure 4, the same on the line 3-4, fig. 1.

Figure 5, the same on the line 5-6, fig. 2; and

Figure 6, a detached portion of the oil-cup.

Similar letters refer to similar parts throughout the several views.

A is the mouth of the oil-cup, and B the reservoir. D is a hollow spindle provided with a suitable handle, E, above which is the head *a* of a set-screw; F, the threads of the latter being adapted to internal threads in the upper end of the spindle D, the interior of which communicates through a lateral opening, *b*, with the external air, the lower end of the set-screw forming a valve adapted to a seat, *y*, in the spindle. This spindle D passes through a ring, C, which is notched on the under side, forming projections which rest in the mouth A of the cup, so that the oil may have a free passage through the notches to the reservoir B under the circumstances described hereafter. Between the mouth A and the ring intervenes an annular piece, H, of wire gauze or perforated plate. Between the ring C and the under side of the handle E intervenes a spiral spring, I, the tendency of which is to elevate the spindle D. That part of the spindle which passes through and is arranged to slide in the neck *d* of the vessel is cut away to the form shown in fig. 3, so that there may be a free communication between the reservoir B and mouth A of the cup when the spindle is depressed. At the lower end of the spindle D is an enlargement, *j*, in which is a transverse hole, *h*, communicating with the interior of the said spindle, and in the end of the enlargement is a square orifice for the reception of the upper square end *i* of a cap, *k*, between a shoulder on which, and the end of the enlargement of the spindle, intervenes the spiral spring *m*. In the cap *k* is a conical recess for the reception of a tapering projection, *n*, on the upper end of a branch, M, to which the oil-cup is secured, this branch as well as its projection being hollow, and having a lateral communication, *p*, with a lateral opening, *p'*, in the cap *k*, and consequently with the interior of the oil reservoir B, under the circumstances referred to hereafter. When the several parts are in the position shown in fig. 2, the communication between the mouth A and reservoir B is closed, as the valve *f* of the spindle D is maintained in contact with the seat *y* by the spiral spring *m*. If a supply of oil has to be discharged from the reservoir B through the branch M, the spindle D is turned by means of the handle E until the opening *p'* of the cap *k* coincides with the opening *p* of the branch M, when a free passage is afforded for the escape of the oil. When the reservoir B has to be replenished with oil, the spindle D is turned until the communication between the reservoir and the branch M is closed, when the operator depresses the spindle D by placing his hand on the head *a* of the set-screw F, at the same time turning the latter, thereby elevating its lower end from the seat in the spindle, when air has free access to the interior of the reservoir B through the opening *b* and through the interior of the spindle and transverse passage *h*, so that whatever oil is poured into the mouth A will at once pass through the wire gauze strainer A in a pure state to the reservoir below. The strainer is maintained in its place during the movements of the spindle by the spring I, but may be readily detached when the spindle is to be removed. By this arrangement of the strainer and spring the use of a set-screws or other additional appliances for securing the strainer is avoided. When the pressure upon the spindle is withdrawn, it will be at once elevated to its former position by the spiral spring *m*, and the communication between the mouth A and the reservoir B will be closed. The spiral spring

m serves to maintain the cap tight on the projection *n*, and the movement of the cap is limited by a pin, *x*, on the bottom of the cup projecting into a recess in the cap.

We do not claim broadly an oil-cup having a hollow stem with openings closed by a valve through which oil is admitted to a reservoir, neither do we claim broadly a strainer in combination with an oil-cup, but we claim as our invention, and desire to secure by Letters Patent—

1. The combination of the spindle D, its valve *f*, cap *k*, spring *m*, projection *n*, and passages *p p'*, the whole being constructed and arranged in respect to the mouth and reservoir of the oil-cup substantially as and for the purpose herein set forth.

2. The combination of the above and the hollow spindle D, its vent-hole *b*, and the set-screw F, for the purpose specified.

3. The ring C, resting with its notched under edge in the mouth A, and forming a rest for the spring I, all as set forth.

4. The detachable annular strainer H, constructed and combined with the ring C, spindle D, and spring I, as described.

In testimony whereof we have signed our names to this specification in the presence of two subscribing witnesses.

ROBERT ROSS,
B. E. LEHMAN.
